CLAIM

I claim the ornamental design for a surface mounting system, as shown and described.

DESCRIPTION

FIG. 1 is a perspective view of a surface mounting system showing my new design;

FIG. 2 is a front view thereof;

FIG. 3 is a right side view thereof;

FIG. 4 is a top view thereof;

FIG. 5 is back view thereof;

FIG. 6 is a left side view thereof; and,

FIG. 7 is a bottom view thereof.

The portions of the surface mounting system shown in broken lines form no part of the claimed design.
